UNLOADER

Filed Dec. 22, 1926

Attorney.

UNITED STATES PATENT OFFICE

GEORGE EDGAR HAZARD, OF ROCHESTER, NEW YORK, ASSIGNOR TO KELLOGG MANUFACTURING CO., OF ROCHESTER, NEW YORK

UNLOADER

Application filed December 22, 1926. Serial No. 156,421.

This invention relates to improvements in unloaders being directed more particularly to an automatically operated unloading device for controlling the pressure in a storage tank or the like which tank is being supplied with compressed air from the compressor.

The primary object of the present invention is the provision of an automatically operated unloading unit of novel construction for automatically controlling the air pressure in a storage tank or the like.

A still further object of the invention is the provision of an automatically operated unloading device for use with a compressor or the like for automatically opening and holding open the air intake valve of a compressor or the like at a predetermined time.

20 A still further object of the invention is the provision of a device of the character described which is cheap and simple to manufacture and highly efficient in operation.

Other novel features of construction and 25 improved results of the invention will appear from the following description and the accompanying drawings.

In the drawings:

Figure 1 is a vertical sectional view 30 through the unloader.

Figure 2 is an end view in side elevation of the device.

Figure 3 is an enlarged view of the bleed-er screw.

35 The present invention is an automatically operated unloading device which has been developed and is primarily used with an air compressor which is in continuous operation. The purpose of the device is to protect the compressor and storage tank so as to prevent the building up of an excessive air pressure which might result in the blowing up of the storage tank. The further and second purpose of the invention is to assure that the 40 compressor will at all times begin its work against zero or atmospheric pressure.

45 Describing the invention in detail it will be seen that the unloading device is provided with an inlet opening 5 which opening 50 is adapted to communicate with an air pipe

(not shown) running to a storage tank (not shown). From this it will be seen that the unloader is at all times in constant communication with the air storage tank. The air inlet opening 5 at its inner side is in 55 communication with two ports or channels 6 and 7. The channel or port 6 terminates in an enlarged circular valve chamber 8 which chamber has an open outer end and is provided with a circumferential seat 9 in 60 which is positioned a closure 10. The outer wall of the chamber 8 is externally threaded as at 23 to receive and support a hollow plug 12.

65 Mounted within the hollow plug and adapted for reciprocation therein is a plunger 13 which plunger is provided internally with a ball 14 upon which is superimposed a coil spring 15, the outer end of which bears against adjusting screw or plug 16, 70 which is internally threaded in the outer end of the plug 12 as at 17. The adjusting screw 16 is provided on its outer face with a slot 18 whereby the screw may be readily turned through the medium of a screw driver or 75 other suitable tool. A locking nut 19 is provided for locking the said screw in its adjusted position.

80 The unloader is provided centrally with an air receiving plunger chamber 20, the inlet channel or opening of which is designated at 21. The inlet channel 21 extends into the chamber 8 in the form of a pipe-like member 22. The inlet end of the channel 21 is normally closed by a valve 11 which is of a U- 85 shape in cross section and is of a width approximately the same as the width of the chamber 8 whereby the side walls of the chamber act as a guide for the valve in its movement. A coil spring 24 surrounds the pipe-like portion of the inlet 22 and exerts a normal outward pressure upon the valve 11.

90 The central chamber 20 has an open lower end which is in communication with the circular chamber 25, the lower end of the chamber being externally screw threaded as at 26 and it is by means of these screw threads that the unloader is fastened in a compressor cylinder head (not shown) above the inlet valve 100

thereof (not shown). The lower end of the chamber 25 is closed by a plug 27 which is externally screw threaded therein as at 28. This plug is held in locked position by means of a set screw 29.

5 Mounted within the chamber 25 and adapted for reciprocation therein is a disc 30 which floats freely on a carrier 31 which carrier is supported upon a plunger rod 32 which is of a length to extend well beyond the closing plug 27 and into the compressor cylinder head for engagement with the compressor inlet valve. The chamber 25 is provided with an internal sleeve 33, the upper end 34 of which forms the seat for the disc 30. The sleeve 33 in turn carries the spider 35 which acts as a guide for the disc carrier 31. A coil spring 36 surrounds the plunger 32 having engagement with the closing plug 27 at one 10 end and the lower end of the disc carrier sleeve 37 at its other end, thus exerting a normal upward pressure upon the disc carrier and disc and holding the disc in closed position against the lower open end of the central chamber 20. A lock nut 38 is provided 15 for locking the unloader in the compressor cylinder head opening.

20 The channel or port 7 heretofore referred to has its lower end normally closed by a hand 30 operated valve 39. The purpose of this hand operated valve is to enable the compressor to be started by hand if there is any pressure in the storage tank, as otherwise the air in the cylinder of the compressor on top of the 35 piston, if it were not relieved, would put an excessive load on the engine or motor driving the compressor and would cause difficulty there or would have a tendency to throw off the driving belt or burn it. By means of 40 this hand operated screw the compressor may be started when the conditions are such as has been just above described.

45 For the purpose of preventing dirt entering the device through the passage 5 and interfering with its operation, a suitable air strainer or filter 41 usually composed of felt, is placed in the passage 5, and this filter is held in position and prevented from clogging up the passages 6 and 7 by means of a suitable screen 41' placed immediately below said filter.

55 Attention is directed to the fact that the upper end of the plunger 32 is within the sleeve 37 of the disc carrier and that the plunger is provided with a reduced upper end 42 that enters the disc carrier so as to cause the plunger and carrier to move together at all times.

60 Attention is directed to a bleeder or regulating screw 44 which passes through the side of the housing 1 and has its inner tapered end 45 adapted to enter an opening 46 formed in the chamber 20. This screw has one side flattened throughout its length as 65 shown at 47 whereby an air passage is formed

between the screw and the wall of its opening. A lock nut 48 serves to lock the bleeder screw in its adjusted position. The object of providing this bleeder screw or member is to cause a difference between the pressure in 70 the chamber 20 and the pressure that is in the storage tank, and therefore causes a differential pressure between that contained in the pressure tank and that contained in the chamber 20, the pressure required to cause 75 the disc 30 to operate its plunger or rod 32.

Attention is further called to the fact that the disc 30 when in its upward position, is seated against a cone-shaped seat 30'. The object of this is that when the disc 30 is unseated, then a larger surface of exposure is created which causes it to act in a snappy and powerful manner and cause the rod 32 to quickly act upon the part which it engages.

80 The cover or top 10 of the chamber 8 is held against its seat by means of a suitable metallic ring 43 which is pressed downward by the member 12 that is screwed in position. In this manner the top or cover 10 is 85 held to its seat and it has only a buckling movement back and forth to cause the valve 11 to be seated and unseated on the pipe-like member 22.

90 I am aware that it is not new to utilize 95 a thin disc or diaphragm acting as a valve adapted to act directly on the outlet member 22 which has a tapered seat for it. In practice however it is found that this construction is not durable because the valve seat 100 soon cuts or wears through the disc. I am also aware that a conical valve has heretofore been used that seats in the conical opening of the member 22. Such a construction 105 however has been found impractical in devices of the character here described because it is very difficult to properly seat the conical valve to make a closure. For this primary reason conical valves are considered as impractical in such a construction. Therefore I have devised the combination of a flexible closure 10 which serves to close the end 110 of the chamber 8 and I place the U-shaped valve 11 composed of the relatively thick non-flexible material located between and its 115 opposite sides in engagement with the tapered seat of the outlet member 22 and the flexible plate or diaphragm 10. I have also found such a valve needs means for accurately guiding and supporting this valve and I accomplish it by making the valve 1120 U-shaped in cross section so that it fits properly against the walls of the chamber 8 and thereby guides this heavier metal valve and also 115 serves to cause the plate valve to accurately fit against the tapered seat of the member 22 thereby insuring at all times an accurate and tight fitting of the parts. It will thus be 125 seen that this construction avoids all of the 130

objections to structures that have been before used in this relation.

Operation

5 The parts having the adjustments here shown, operate as follows: The pressure being built up in the pressure tank, flows through the passageway 5, the strainer 41 and the passage 6 and the pressure then acts 10 against the underside of the U-shaped valve 23. When the pressure in the storage tank has reached its limit, the pressure in the chamber 8 lifts the valve 11, when the pressure 15 will flow through the pipe-shaped member 21 into the chamber 20. A part of this pressure is allowed to escape by means of the bleeder screw 44. The pressure in the chamber 20 acting on the disc 30, causes it to move 20 from its seat 30', which being cone-shaped, the diameter of the disc is increased, causing it to act in a snappy manner and with power on the rod 32. All the time that the pressure tank is unloading, air is escaping 25 by this bleeder screw 44, thereby causing a differential pressure between the pressure of the storage tank and the pressure of the chamber 20, whereby the pressure in the chamber 20 is less than the pressure in the storage tank, causing the disc 30 to return 30 upward to the position shown in the drawings. When the disc 30 is moved downward, it finally reaches the member 34 against which the valve seats.

While I have described my construction in 35 detail, I do not desire to limit myself since changes and variations may be made without departing from the invention so long as the changes may be within a fair interpretation of the appended claims.

40 Having thus described my invention, what I desire to claim and secure by Letters Patent is:

1. An unloader adapted for use with air compressors or the like, comprising a casting 45 having therein an air inlet in communication with a chamber, an air outlet from said chamber to a second chamber, a valve arranged in said first chamber and adapted to normally close the outlet pressure, a disc positioned below said second chamber, a carrier for said disc, a guide for said carrier, a plunger having connection with said carrier, and resilient adjustable means for normally holding the valve in a closed position in respect to the 50 outlet opening from the first chamber, whereby a predetermined amount of air is required to unseat said valve to cause the operation of the disc and the plunger.

2. An unloader adapted for use with a 55 compressor or the like, comprising a casting having therein a valve chamber and a second chamber, an inlet adapted to receive air pressure in communication with said valve chamber, communication between said valve 60 chamber and said second chamber, a valve

in said valve chamber adapted to normally close communication between said chambers, a housing having communication with said second chamber, a disc mounted in said housing and adapted for reciprocation therein, a 70 carrier for said disc and a guide for said carrier, a plunger having connection with said carrier and adapted for engagement with the inlet valve of the compressor, and adjustable resilient means for normally holding the valve in the valve chamber in a closed position, whereby a predetermined amount of air is required to unseat said valve.

3. An unloader adapted for use with a compressor or the like, comprising a casting having therein a valve chamber and a second chamber, an air inlet in communication with a pressure supply at one end and said valve chamber at its other end, an air passage providing communication between the valve chamber and the second chamber, said passage having an extending end into the valve chamber, a valve in said valve chamber normally seated upon said extending end to close the same, said valve being U-shape in cross section and guided throughout its movement by the side walls of the valve chamber, a housing mounted below the second chamber and having therein a seat, a plunger in said housing, a disc carrier mounted upon said plunger, a disc mounted upon said carrier, a guide for said disc carrier, means to normally hold said plunger, disc carrier and disc in elevated positions, and adjustable resilient means to normally hold the aforesaid valve in a closed position upon its seat, whereby a predetermined amount of air pressure is required to unseat said valve to permit the passage of air to the second chamber for operating the members in said housing.

4. An unloader comprising a housing having a valve chamber and an air receiving passageway communicating therewith, said chamber having an air outlet with one end projecting within said chamber and its outer end in communication with a second chamber, a flexible member closing the said valve chamber, a U-shaped valve of heavier metal than the said flexible member for the purpose described located between said flexible member and the outer end of said projecting outlet and adapted to seat on the said projecting outlet, means for constantly exerting pressure on said valve to cause it to normally be seated, and a plunger mechanism in communication with the said second chamber.

5. An unloader of the type described comprising a housing having a valve chamber and an air receiving passageway communicating with said chamber, an outwardly projecting outlet having a tapered outer end communicating with the said chamber and its inner end communicating with a second chamber, a flexible member closing the outer end of said first mentioned chamber, a 130

- U-shaped valve of relatively heavier material than the said flexible member located between the said flexible member and said outwardly projecting outlet and in engagement therewith, the inner side of the said valve being adapted to seat on the tapered projecting end of the outlet, means for pressing the said flexible member and thereby said valve in engagement with its said seat, said second 5 chamber having one end open, a cylinder in communication with the said chamber and of considerably larger diameter than the said chamber, said open end having its outer end tapered outwardly, a plunger in the said cylinder, a disc carried by the said plunger and fitting within the said cylinder whereby an increased pressure on the disc is effected when it moves off its seat adjacent said second chamber.
- 10 6. A compressor unloader comprising a housing provided with a chamber having an air inlet, said chamber having a passageway establishing communication between it and a second chamber, a valve controlling said last 15 chamber having one end open, a cylinder in communication with the second chamber, a constantly open bleeder passageway in communication with the second chamber for the purpose of establishing differential pressures between the two chambers, and a manually operated valve for said bleeder passageway adapted to establish communication between the air inlet and the second chamber by manual operation to relieve the pressure 20 in the compressor when the same is started, for the purpose described.
- 25 In testimony whereof I hereunto affix my signature.
